UNITED STATES PATENT OFFICE

IRVING E. GROSSMAN, OF NEW YORK, N. Y.

DESIGN FOR A SHOE

Application filed March 17, 1933. Serial No. 47,484. Term of patent 3½ years.

To all whom it may concern:

Be it known that I, IRVING E. GROSSMAN, a citizen of the United States, residing in New York, in the county of New York and State of New York, have invented a new, original, and ornamental Design for a Shoe, as of which the following is a specification, reference being had to the accompanying drawing, forming part thereof.

I claim:

The ornamental design for a shoe, as shown.

IRVING E. GROSSMAN.
